UNITED STATES PATENT OFFICE.

ADOLPH E. ASHLEMAN AND THOMAS E. HANEY, OF WACO, TEXAS.

SIGNAL.

Application filed October 22, 1926. Serial No. 143,433.

This invention relates to signaling devices, and more particularly to a signaling device especially designed for use in connection with closed motor vehicles, the primary object of the invention being to provide a signaling device which will simulate the movements of the operator's hand in signaling to operators of approaching vehicles, the movement to be taken by the vehicle.

Another important object of the invention is to provide a device of this character which, when the operating rod is moved, will cause the pivoted hand section to take various positions of adjustment, means being provided for temporarily holding the hand in such adjusted position.

Still another object of the invention is to provide a signaling device which may be readily and easily operated by the driver of the vehicle, from a point within the motor vehicle body, with the minimum amount of exertion on the part of the operator.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of a signaling device constructed in accordance with the invention, the same being shown in its normal or inactive position.

Figure 2 is a sectional view taken on line 2-2 of Figure 1.

Figure 3 is a sectional view taken on line 3-3 of Figure 1.

Figure 4 is a sectional view taken on line 4-4 of Figure 1.

Figure 5 is a rear elevational view of the signaling device, the cover plate thereof having been removed.

Figure 6 is a view illustrating the signaling device in one of its adjusted positions, or in a position indicating "stop".

Figure 7 is an elevational view, cover removed, and indicating the hand section in dotted lines as indicating "right turn" and in full lines indicating "left turn".

Figure 8 is a sectional view taken on line 8-8 of Figure 7.

Referring to the drawings in detail, the device includes a body portion formed of a forward section 5 and a rear section 6, the forward section 5 being constructed of a length of sheet metal having its side edges bent upwardly, providing a casing for the operating mechanism to be hereinafter more fully described.

The forward end of the section 5 is circular in formation and is provided with a central opening through which the bolt 7 extends, which bolt pivotally connects the section 5 and movable arm section 8. This movable section 8 also embodies a length of sheet metal having one of its edges bent at right angles as at 9 providing a flange to be engaged by the hand section 10 to restrict movement of the hand section when it is being moved to its inactive position.

The section 8 is formed with a cut away portion 11 defining shoulders 12 and 13 respectively, which shoulders are adapted to engage the bolt 14 that extends through the section 5 and on which the lever 15 is pivoted, there being provided a spacing collar on the bolt to hold the lever 15 in spaced relation with the section 5 to permit the movable sections to move therebehind.

As clearly shown by Figure 6 of the drawings, the lever 15 has its forward end extended to a point adjacent to the bolt 16 that pivotally connects the hand section 10 and section 8 of the signaling device. An elongated opening indicated at 17 is formed in the section 10 and accommodates the bolt 18 that connects the lever 15 and section 10, the connection between the lever 15 and section 10 being such that sliding movement of the lever as well as a swinging movement, with respect to the section 10 will be permitted.

An enlargement 19 is formed at one end of the lever 15 and is provided with lugs 20, the lower end of the enlargement operating within the guide bar 21, which embodies spaced side members spaced apart to accommodate the enlargement 19, there being provided an opening 22 for the reception of the lug 20 as shown by Figure 7, so that when the lever 15 is moved to a position as shown by Figure 7, the pivoted sections will be temporarily held in such position.

When the operating mechanism is moved to a position as shown by Figure 6, the lower shoulder 13 is in engagement with the bolt 14 restricting further downward movement of this section 8.

When the pivoted section 10 is moved to a position as shown in dotted lines in Figure 7, the bolt 18 assumes such position with respect to the section 10 that the section 10 will not move to its lower position by gravity, owing to the pressure exerted on the member 21 and enlargement 19 by the coiled spring 23.

As clearly shown by sheet 2 of the drawings, the operating mechanism includes a bar 24 having a right angled end 25 formed with an opening to accommodate the upper end of the spring 23, while the lower end thereof passes through an opening formed in the member 21, the member 21 having pivotal connection with the bar 24 at 26.

The enlargement 19 is formed with an opening to accommodate the pivot pin 27 that connects the right angled portion 25 and enlargement 19, with the result that when inward movement is imparted to the member 25, the lever 15 will swing on the bolt 14 according to the direction of the movement of the right angled portion 25.

At the upper and lower ends of the bar 24 are enlargements 28 that ride in grooves formed in the inwardly extended end portions of the casing 5, the grooves acting as guides for the member 24 to insure the true operation of the device.

An opening is formed adjacent to the upper end of the bar 24 and accommodates one end of the connecting link 29, the opposite end thereof being connected to the upper end of the pivoted arm 30. This arm 30 is formed with an elongated opening 31 in which the offset portion or crank 32 of the operating rod 33 moves, the operating rod carrying the hand piece 34 on its outer end for the convenient operation of the device.

This link 29 is shown as extending through the bearing 35 positioned in an opening formed in the side of the vehicle body.

It might be further stated that the sections of the housing or body portion are secured to opposite surfaces of a side of a closed vehicle body, as by means of the bolt 36 and tubular bearing 35 which is shown as having nuts 37 on its ends to clamp the sections to the body.

From the foregoing it will be obvious that by rotating the hand piece 34, the signal may be moved to various positions as indicated by Figures 5, 6 and 7 of the drawings, signaling to the operators of approaching vehicles, the direction of travel or movement to be taken, by the vehicle equipped with the device.

In order that the signaling device will be readily seen by persons approaching the ve-

hicle from the rear, a glass member 38 is positioned adjacent to the outer end of the section 8, the glass member 38 being formed with a plurality of faces to reflect light rays directed thereto. This glass member 38 is preferably formed of a colored glass such as red to make the same clearly visible.

A mirror 39 is secured to the outer end of the section 5 so that the operator of the vehicle may have a clear view of the road surface at the rear of the vehicle.

We claim:

1. In a signaling device, a body portion, an arm section pivotally connected with the body portion, a hand section pivotally connected with the arm section, a lever pivotally supported at one end of the body portion and having pivotal connection with the hand section, a pivoted member in which a portion of the lever moves, to guide the lever, a coiled spring for exerting an upward pressure on the lever to secure the lever in its positions of adjustment, and means for operating the lever to move the arm section and hand section.

2. In a signaling device, a body portion, an arm section pivotally connected with the body portion, a hand section pivotally connected with the arm section, a lever having pivotal connection with the hand section and having an enlargement at one of its ends, a bolt extending through the enlargement to pivotally connect the lever to the body portion, a guiding member including spaced flanges, one edge of the enlargement being disposed between the flanges to guide the lever, means connected with the lever for moving the lever to operate the arm section and hand section, and a coiled spring for urging the guiding member into close engagement with the enlargement to hold the sections in their positions of adjustment.

3. In a signaling device, a body portion, an arm section pivotally connected with the body portion, a hand section pivotally connected with the arm section, a lever, a bolt for pivotally connecting the lever to the body portion, said lever adapted to operate to move the hand section and arm section to various positions of adjustment, said arm section having shoulders adapted to engage the bolt to restrict movement of the arm section, means for exerting a pressure on the lever to retard the movement of the lever to hold the sections in their positions of adjustment, and means for operating the lever.

4. In a signaling device, a body portion, an arm section and a hand section supported by the body portion, an operating means including a lever having lugs extending from one edge thereof, a guiding member contacting with the lever and having openings to receive the lugs, means for urging the guiding member into engagement with the lever to restrict movement of the lever, and said

lever adapted to be operated to move the arm and hand section.

5. In a signaling device, a body portion, an arm section and a hand section supported for pivotal movement by the body portion, a bell crank lever supported within the body portion, a lever having an enlargement at one end, means for pivotally connecting the lever through the enlargement to the bell crank lever, spaced lugs extending downwardly from the enlargement, a guiding member having openings to receive the lugs, a coiled spring connected with the bell crank

lever and the guiding member to normally urge the guiding member upwardly into 15 frictional engagement with the enlargement, and said lugs adapted to automatically move into the openings of the guiding member to hold the lever, arm section and hand section in adjusted positions.

6. In testimony that we claim the foregoing as our own, we have hereto affixed our signatures.

ADOLPH E. ASHLEMAN.
THOMAS E. HANEY.
